AMALGAM CARRIER

Bruce W. Rutrough, Roanoke, Va.

Application May 14, 1940, Serial No. 335,128

7 Claims. (Cl. 32—60)

This invention relates to dental tools, and more particularly, to amalgam carriers for placing amalgam in cavities in teeth.

Dental tools or instruments must meet several requirements. They must be small and so designed as to reach all parts of the mouth; they must be adapted to easy and perfect sterilization; and they must have no exposed moving parts which might pinch or cut the mouth of the patient. All of these requirements are of the utmost importance.

The purpose of this invention is to provide an amalgam carrier which will meet these requirements. The invention contemplates a small instrument for the transportation of amalgam, or other soft filling, to a cavity in a tooth. The instrument is so designed that all moving parts in that portion of the instrument which enters the mouth are completely housed to ensure protection to the mouth of the patient. For proper sterilization, all parts of an instrument must be disassembled and placed in a sterilizer separately. The ease with which the instrument may be assembled or disassembled often determines whether or not it receives proper sterilization. The entire instrument of the present invention may be readily disassembled into its component parts for cleaning and sterilization. This feature also adds to the ease with which worn or broken parts may be replaced.

This in broad terms is the purpose of the invention. For details of construction, attention is directed to the accompanying drawing in which:

Figure 1 is a side elevation of a preferred embodiment of the invention;

Figure 2 is a longitudinal section through the instrument to an enlarged scale, a portion of the handle being broken away;

Figure 3 is a front end elevation; and

Figure 4 is a horizontal section on the line 4—4 of Figure 2.

As the great majority of cavities in teeth are prepared for filling through the use of an electric drill, the instrument embodying the concepts of the present invention is designed to follow as closely as possible the general configuration of the electric drill.

It will be seen from the drawing that the body portion of the instrument is a housing 5, separable along its longitudinal center line into an upper section 6 and a lower section 7. One of the sections of the housing has a tongue 8 depending from its forward end adapted to fit into a matching depression 9 in the other section to

keep the forward portion of the sections in proper alignment. The rear ends of the sections, when together, form a screwthreaded boss 10 of less diameter than the housing. A handle 11 having a screwthreaded bore 12 threads over the boss 10 to clamp the sections of the housing tightly together. This housing provides a cover for all moving parts of the device to protect the mouth of the patient and prevent filling or other matter from clogging the parts.

Pivotedly mounted on a pin 13 passing through the lower section of the housing, is an operating lever 14. One arm of the lever extends downwardly and rearwardly as at 15 through a slot 17 in the lower half of the housing to form an operating trigger, while the arm 16 of the lever extends forwardly to engage a plunger 17. The plunger 17 is mounted for reciprocation within an amalgam receiving chamber 18 contained in a head 19 which is threaded in an opening in the underside of section 7 of the housing, as at 20. It will be noted that the longitudinal axis of the amalgam receiving chamber and consequently the movement of the plunger is at right angles to the axis of the body portion of the instrument, and that the force applied to the plunger by the lever is longitudinal of the amalgam chamber.

To ensure smooth operation of the plunger 17, as well as ease of assembly and disassembly, the plunger is provided with a reduced neck 21 and a tapered head 22. Lever 14 has at its forward end a slot 23 to receive the neck 21 of the plunger 17. Movement of the lever 14 by means of the trigger 15 will impart a reciprocating motion to the plunger. In its downward movement the lever will bear against the shoulder 24 on the plunger, while in its upward movement the lever will rock against the tapered head 22. The tapered head allows for rocking movement between the lever and the plunger thus eliminating binding.

A spring 25 is interposed between the housing and the trigger 15 of the lever, held in position by a boss 26 on the housing and a boss 27 on the trigger. This spring exerts pressure against the lever to maintain the plunger in normal raised position.

In the use of the device, amalgam which has been prepared for filling, may be placed upon any flat surface and the amalgam receiving chamber pressed onto it. This will force a certain amount of the amalgam into the chamber. When a sufficient amount of the filling has been placed in the chamber, the instrument is inserted in the mouth with the amalgam chamber directly over

the cavity in the tooth. Pressure upon the trigger 15 will force the plunger downwardly through the chamber, expelling the filling into the tooth. The amalgam is then condensed or packed with other instruments, and this operation is continued until the cavity is properly filled.

After the dentist has finished treating a patient, it is necessary that the instrument be sterilized before it is used on another patient. For complete sterilization, the instrument must be completely disassembled and the various parts placed in the sterilizer separately. To disassemble the instrument, the handle 11 is first unscrewed and taken off, leaving the two sections of the housing readily separable. The pivot pin 13 of the lever 14 is pulled out and the lever moved backward in the slot 7, releasing the plunger 17 from the lever. The head 19 is removed from the section 7 of the housing completing the disassembling of the instrument. By reason of the construction employed, all portions of the instrument will be separated, there will be no joint or crevice in which bacterial may lodge, and all parts may be readily sterilized. After sterilization the parts may be easily reassembled for use.

Although a preferred embodiment of the invention has been shown and described, changes may be made within the scope of the appended claims.

What I claim is:

1. An amalgam carrier comprising a split housing, a handle removably secured to one end of said housing to clamp the housing together, a head having an amalgam receiving chamber removably secured to the opposite end of said housing, a lever pivotally mounted in the housing, and a plunger carried by said lever for reciprocation within the amalgam receiving chamber.

2. An amalgam carrier comprising a housing having separable sections, one of said sections having an amalgam receiving chamber removably secured thereto, a lever pivotally mounted in said housing and carrying a plunger for reciprocation in the amalgam chamber, and a handle removably secured to said housing to clamp the sections together.

3. An amalgam carrier comprising a housing, a lever pivotally mounted in said housing, and a head having an amalgam receiving chamber, said housing comprising separable sections having matching threaded portions, and a handle having a threaded bore to receive the threaded portions of said housing and clamp the sections together, said lever having a plunger removably secured thereto for reciprocation within the amalgam receiving chamber, and a spring between said housing and said lever.

4. An amalgam carrier comprising a housing, a lever pivotally mounted in said housing and a handle, said housing comprising separable sections having matching threaded portions, and a

head having an amalgam receiving chamber removably secured to one of said sections, said handle having a screwthreaded bore to receive a threaded portion of the housing and clamp the sections together, a plunger removably secured to the lever for reciprocation within said amalgam receiving chamber, and a spring between said housing and said lever.

5. An amalgam carrier comprising a housing portion, a handle portion secured to the rear end of the housing portion, said housing portion being provided in its bottom with a slot located adjacent to its rear end, a head having an amalgam receiving chamber secured to and depending from the housing portion adjacent to its front end, a lever pivotally mounted in the housing portion adjacent to the slot and having an actuating arm enclosed in the housing portion and a trigger projecting outwardly and downwardly from the housing portion through said slot, and a plunger connected within the housing portion to the actuating arm of said lever for reciprocation within the amalgam receiving chamber.

6. An amalgam carrier comprising a housing formed of longitudinally divided separable upper and lower sections, the lower section having a slot in the bottom thereof, means at the forward ends of the sections to detachably interconnect them when assembled against relative displacement, a detachable handle engaging and clamping the housing sections together at their rear ends, a lever pivotally mounted upon the lower housing section and having an actuating arm enclosed in said housing and a trigger projecting from the housing through said slot, a plunger connected to said actuating arm of the lever, and a head having an amalgam receiving chamber to coact with the plunger, said head being removably secured to the bottom of the lower section of the housing and depending therefrom.

7. An amalgam carrier comprising a housing formed of longitudinally divided separable upper and lower sections, the lower section having a slot in the bottom thereof, means at the forward ends of the sections to detachably interconnect them when assembled against relative displacement, a detachable handle engaging and clamping the housing sections together at their rear ends, a lever pivotally mounted upon the lower housing section and having an actuating arm enclosed in said housing and a trigger projecting from the housing through said slot, a spring extending through the slot and bearing upon the housing and trigger to normally hold the lever in retracted position, a plunger detachably connected to said actuating arm of the lever, and a head having an amalgam receiving chamber to coact with the plunger, said head being removably secured to the bottom of the lower section of the housing and depending therefrom.

BRUCE W. RUTROUGH.
